US00D792378S

(12) **United States Design Patent** (10) **Patent No.:** **US D792,378 S**
Brunner et al. (45) **Date of Patent:** **** Jul. 18, 2017**

(54) **EARPIECE**(71) Applicant: **Apple Inc.**, Cupertino, CA (US)(72) Inventors: **Robert Brunner**, San Francisco, CA (US); **Christopher Kuh**, San Francisco, CA (US)(73) Assignee: **Apple Inc.**, Cupertino, CA (US)(***) Term: **15 Years**(21) Appl. No.: **29/540,941**(22) Filed: **Sep. 29, 2015****Related U.S. Application Data**

(60) Continuation of application No. 29/496,755, filed on Jul. 16, 2014, now Pat. No. Des. 741,299, which is a continuation of application No. 29/441,334, filed on Jan. 3, 2013, now Pat. No. Des. 712,382, application No. 29/540,941, which is a continuation of application No. 29/501,037, filed on Aug. 29, 2014, now Pat. No. Des. 740,260, which is a division of application No. 29/441,334, filed on Jan. 3, 2001, now Pat. No. Des. 712,382.

Primary Examiner — Paula Greene(74) *Attorney, Agent, or Firm* — Sterne, Kessler, Goldstein & Fox P.L.L.C.(57) **CLAIM**

The ornamental design for an earpiece, as shown and described.

DESCRIPTION

FIG. 1 is a top rear perspective view of an earpiece showing our new design;

FIG. 2 is a front view thereof;

FIG. 3 is a rear view thereof;

FIG. 4 is a side perspective view thereof;

FIG. 5 is a top view thereof; and,

FIG. 6 is a bottom view thereof.

The broken lines depict portions of the earpiece and environment that form no part of the claimed design.
